UNITED STATES PATENT OFFICE.

JAMES LOUIS PIERCE, OF MANILA, PHILIPPINE ISLANDS, ASSIGNOR TO PACIFIC COMMERCIAL COMPANY, OF MANILA, PHILIPPINE ISLANDS, A CORPORATION OF PHILIPPINE ISLANDS.

DRYING APPARATUS.

1,254,431.

Specification of Letters Patent. Patented Jan. 22, 1918.

Application filed December 28, 1916. Serial No. 139,239.

To all whom it may concern:

Be it known that I, JAMES L. PIERCE, a citizen of the United States, and a resident of Manila, in the Philippine Islands, have 5 invented certain new and useful Improvements in Drying Apparatus, of which the following is a specification.

My invention relates to drying apparatus or evaporators, in the present instance for 10 copra, and one of the main objects thereof is to provide means for supplying pure heated air to the copra and to provide means for maintaining said heated air at a high temperature by means of the heated gases produced 15 by the combustion of the fuel in a furnace.

Another object is to provide the passages 20 for the gases in the form of tortuous pipes in sets superposed one above another, and to provide compartments between said pipes in each set for the heated atmospheric air, said 25 compartments being perforated to permit the escape of the heated air therefrom to act upon the copra.

Another object is to provide a plurality of 30 superposed copra conveyers traveling in different directions whereby the copra is deposited upon each conveyer successively and carried the length of the apparatus to insure a maximum travel to the copra while the 35 moisture is being extracted therefrom.

My drying apparatus is adapted to be used with any desired type of furnace though is particularly adaptable to the form shown and described in an application for patent 40 filed by me herewith.

My invention is fully described in the following specification, of which the accompanying drawings form a part, in which like characters refer to like parts in each of the 45 views, and in which:

Figure 1 is a side elevation of one embodiment of my apparatus, partly in section;

Fig. 2 is an end elevation, partly in section on the line 2—2 of Fig. 1;

Fig. 3 is a section taken on the line 3—3 of Fig. 1, partly showing structural parts thereover;

Fig. 4 is an end elevation; and

Fig. 5 is an enlarged section, fragmentarily, taken on the line 5—5 of Fig. 3.

Referring to the drawings, 6 represents a housing having a pipe 7 leading thereto for conveying heated pure air to the apparatus from a suitable furnace, not shown,

and a pipe 8 connected to a vertical pipe 9 55 for conveying heated gases and smoke from the fuel in the furnace to said apparatus, the pipe 9 having a plurality of spaced branches 10 leading therefrom and entering the housing at different heights and the pipe 9 has a 60 plurality of partition plates 11 suitably arranged therein for a purpose to be explained.

Each pipe or branch 10 is looped within the housing, in its particular horizontal 65 plane, and joined to a vertical pipe 12 at the opposite side of the housing and adjacent the opposite end from that occupied by the pipe 9, and said pipe 12 is likewise provided with suitably arranged partition plates 13 70 and has its upper end open to the outer air.

Joining the pipe sections in each horizontal plane are upper and lower plates 14 and 15 the former of which is perforated, thus 75 forming compartments between the pipe sections the ends of said compartments being closed as shown at 16, Fig. 3, and a pipe 17 leads into one end of one compartment and a pipe 18 into the opposite end of the other compartment, of each set of pipes 10 in each 80 horizontal plane.

The pipes 17 are all connected with a stand-pipe 19 joined at its lower end to the hot air pipe 7 whereas all of the pipes 18 are connected with a stand-pipe 20 adjacent 85 the other end of the apparatus likewise joined to the hot air pipe 7, and it will be seen that the heated pure air from a furnace, under pressure as by means of a blower, is forced into all of the compartments between the respective smoke and gas pipe sections and thence upwardly out of said compartments through the perforations in the plates 14.

The smoke and gases from the furnace are 95 conveyed through a tortuous path from the stand-pipe 9 to the stand-pipe 12, and reversely in alternate planes, the several portions in the stand-pipes 9 and 12 limiting upward movement of the smoke and gases 100 to the successively higher planes, and it will thus be seen that a maximum travel of the heated products of combustion is insured through the apparatus, with the consequent effect of maintaining the interior of the 105 housing at a higher temperature than would be the case were the pure air pipes alone provided.

Arranged adjacent the top of the housing is a horizontal conveyer 21 having one end extended outwardly of said housing, and of the endless belt type, with the carrying portion thereof arranged slightly above the uppermost perforated plate 14, Fig. 1, and adjacent the bottom of the housing is a similar conveyer 22 likewise extended beyond said housing and having its carrying portion arranged immediately above the lowermost perforated plate 14.

Interposed between the conveyers 21 and 22 are a plurality of conveyers 23, one in the position of each of the perforated plates 14 in the several horizontal planes, and said conveyers are caused to travel simultaneously, with alternate conveyers in opposite directions.

The material to be dried is fed to the upper conveyer 21 and falls from the inner end thereof to the next lower conveyer 23, being guided thereon by means of a curved plate 24, and to the successively lower conveyer 23 until the dried material is deposited upon the conveyer 22 and carried outwardly of the housing, a maximum degree of travel having resulted whereby a maximum degree of heat application or drying results, and the hot air from the uppermost plates 14 of the several compartments escapes from the housing through a vent 25, Fig. 2.

The endless conveyers are shown as mounted upon rollers 26 and 27 and I prefer to make the latter adjustable in order to adjust

the tension on the respective conveyers, no means being illustrated as many forms thereof might be used.

Having fully described my invention, what I claim as new, and desire to secure by Letters Patent, is:—

1. In a drying apparatus, a housing, a plurality of superposed conveyers, a heating unit arranged adjacent each conveyer, means for leading heated air to said units, and supplemental heating means for said units.

2. In a drying apparatus, a housing, a plurality of superposed conveyers, a heating unit arranged adjacent each conveyer, means for leading heated air to said units, and means for leading the products of combustion to said units for supplementing the latter, without mixing therewith.

3. In a drying apparatus, a housing, a plurality of superposed conveyers, a feed pipe for heated gases, a stand-pipe connected therewith, a supplemental stand-pipe, a plurality of coiled pipes joining said stand-pipes and arranged adjacent the respective conveyers, said last named stand-pipe being open to the air, means in said stand-pipes for directing the gases through the successive coiled pipes from bottom to top, plates joining the convolutions of said coiled pipes to form compartments therebetween, and means for leading heated air from a furnace to all of said compartments.

JAMES LOUIS PIERCE.

Copies of this patent may be obtained for five cents each, by addressing the "Commissioner of Patents, Washington, D. C."
